UNITED STATES PATENT OFFICE.

ALLEN B. PIERCE, OF SYRACUSE, NEW YORK.

PRESSING-MACHINE.

1,362,735

Specification of Letters Patent. Patented Dec. 21, 1920.

Application filed July 16, 1919. Serial No. 311,131.

To all whom it may concern:

Be it known that I, ALLEN B. PIERCE, a citizen of the United States, and a resident of Syracuse, in the county of Onondaga and 5 State of New York, have invented a certain new and useful Pressing-Machine, of which the following is a specification.

This invention relates to garment pressing machines and has for its object a machine in 10 which garments or clothes may be pressed between flat surfaces or curved surfaces, which machine is particularly simple in construction, readily convertible to bring flat or curved surfaces into pressing position, and 15 highly efficient and durable in use; it consists in the novel features, and in the combinations and constructions hereinafter set forth and claimed.

In describing this invention, reference is 20 had to the accompanying drawings, in which like characters designate corresponding parts in all the views.

Figures 1 and 2 are respectively front and side elevations of a pressing machine 25 embodying my invention.

Fig. 3 is an enlarged sectional view taken approximately on the plane of line 3—3, Fig. 1.

Fig. 4 is a transverse sectional view 30 through the upper and lower bucks and the intermediate pressing element.

Fig. 5 is a sectional view partly in elevation taken approximately on the plane of line 5—5, Fig. 3.

35 In pressing garments, it is necessary to press parts of the garment between two flat surfaces, and other parts between concave and convex surfaces. For instance, in pressing a coat it is preferable to press the back 40 and front of the coat between flat surfaces and the shoulders between rounding surfaces.

In my machine, all the pressing operations 45 can be performed upon one machine and steam can be injected into or onto the garment to facilitate the pressing operation.

This machine comprises generally, upper and lower pressing elements, the upper pressing element being movable toward and from 50 the lower, an intermediate element supportable on the upper face of the lower pressing element or adjacent the lower face of the upper pressing element, means for connecting the intermediate element to or disconnecting the same from the upper pressing ele-

ment, and means for passing a heating medium as steam through either the upper or the lower face of the intermediate pressing element.

1, 2 and 3 are respectively the upper, lower and intermediate pressing elements, the element 1 being usually called the upper buck or pressing head and the element 2 the lower buck. The elements 1 and 2 are usually formed with one or more internal chambers 60 through which a heating medium as steam is circulated from a suitable source of supply.

The lower buck 2 is mounted on a standard or what is sometimes called a goose neck 70 4 mounted on a table 5 which is supported by a suitable frame as front and rear legs 6, 7.

The upper buck or pressing head 1 is suitably carried on the front arms 8 of the lever 9 pivoted at 10 between its ends, and the lever 9 being bifurcated and having bearings on the pivots 10, these pivots being mounted in the upper ends of bifurcations 11 of the rear leg 7. The front arms 8 of 80 the lever 9 are suitably connected to the pressing head in any well known manner.

The lever 9 is actuated about its pivot 10 by suitable mechanism, here shown as toggle levers 12 and 13 pivoted together at 85 14 at like ends and at their opposite ends at 15 to the rear arm of the lever 9, and at 16 to the frame or the lower end of the rear leg 7 thereof, the lever 13 having a forward extension 13^a which constitutes a pedal lever 90 for actuating the toggle.

The lever 9 is provided with a suitable counterweight 17 and also a spring 18 is connected to the frame and to the toggle lever 13 or the extension 13^a thereof and tends to 95 actuate the toggle levers to fold the same and hence move the pressing head upwardly.

The link 12 is composed of sections which are connected by a turnbuckle device 12^a for lengthening and shortening the link 12 to 100 adjust the pressure of the pressing head 1 and also to adjust the joint 14 of the toggle relatively to the dead center line of the toggle. This feature forms no part of my invention.

The intermediate pressing element 3 is 105 formed with an internal chamber 3^a through which a heating medium as steam circulates and also with passages 19, 20, which open into chambers 21, 22, on opposite sides of 110

the element 3, these chambers having their outer sides formed with perforations 23, 24.

As shown, the outer sides of the chambers 21, 22 are formed by perforated plates 25, 26, mounted on the body or major portion of the element 3, the opposite sides of which are recessed to form the chambers 21, 22.

In the illustrated form of my invention, one of the pressing elements 1, 2, and as here 10 shown, the lower pressing element or buck 2 is formed with a convex upper face and the intermediate pressing element is formed with a concave lower face conforming to the convex face of the lower buck 2; the 15 upper face of the intermediate element 3 is formed flat to coat with the flat lower face of the upper pressing element or buck 1; and the element 3 is supported on either the upper face of the lower buck 2 or contiguous 20 to the lower face of the upper buck 3.

Means is provided for connecting the intermediate element 3 to the upper pressing element or buck 1 whereby said intermediate element moves as a unit with the upper 25 pressing element or buck 1.

In the illustrated form of my invention the intermediate element 3 is supported by arms 27 mounted on the pivots 10 of the lever 9 which supports the upper buck 1, and 30 means is provided for connecting the arm 27 to and disconnecting the same from the lever 9.

This means may be of any suitable form, size and construction and in the illustrated 35 form of my invention, it includes a lock 28 mounted upon a vertical pivot 29 carried by the rear arm of the lever 9 and movable over the rear arm or yoke 30 of the supporting lever or arm 27 for the intermediate 40 pressing element 3.

The lock 28 is moved into and out of operative position by means of a handle 30^a mounted on the top of the upper pressing element or buck 1 and a rod 31 connecting 45 the handle 30^a to an arm 32 mounted on the upper end of the pivot 29. The handle 30^a is usually mounted upon the pivot 33 connecting the front arms 8 of the lever 9 and the upper pressing head or buck 1. The 50 rear ends of the arms 27 are connected by the yoke 30 located within the bifurcations of the lever 9 and the lock 29 is carried by the lever 9 in position to coat or pass over the intermediate part of the yoke.

55 A suitable counterbalancing spring 35 is connected to the rear arm or yoke of the lever 27 and to the frame or rear leg 7 thereof.

Steam passes from the source of supply 60 through the pressing elements 1, 2, 3, and in the illustrated embodiment of my invention the steam passes in at 36 through the conduit 37 arranged in axial alinement with the pivots 10 through one pivot 10 which is hollow, thence through the passage 38 into the 65 steam chamber 3^a of the intermediate press-

ing element, thence out through the passage 39 in the other bifurcation of the arm 27 outwardly through the other hollow pivot 10 to the outlet pipe 40.

The steam also circulates from the pipe 37 70 to the pipe 40 through the upper buck or pressing head 1 through inlet and outlet pipes 41, 42, the pipes 37 and 40 having suitable joints or couplings 43, 44 therein to which the pipes 41, 42 are connected respectively. 75

The steam is conducted to and from the chamber of the lower buck in any suitable manner.

When the lock 28 is in its inoperative position so that the pressing element 3 is permitted to remain resting on the lower pressing element or buck 2, and the garment is being pressed between the flat surfaces of the upper pressing element, or buck 1 and 80 the intermediate element 3, steam can be passed through the garment or material being pressed, such steam passing through the passages 19, chamber 21 and perforations 23. These passages 19, 20 are formed in the 85 supporting arms 27 for the element 3.

When the lock 28 is moved into its operative position, as seen in Fig. 2 so that the intermediate pressing element 3 moves as a unit with the upper pressing element or buck 1 and hence the garment pressed between the curved surfaces of the intermediate element 3 and the lower buck 2, steam can be then passed through the garment through the passages 20 to the chamber 22 100 on the lower side of the intermediate element 3 and through the perforations 24.

The passage of the steam through the passages 19, 20, is controlled by normally closed spring pressed valves 45, 46, located 105 in the supporting arms 27 for the intermediate pressing element 3 in alinement with the pivots 10. The means for opening the valves consists of a lever 47 pivoted at 48 and having one arm thereof extending between the opposing ends of the valve stems 49, 50 of the valves 45, 46, a handle 51 mounted on the top of the upper pressing head and connected by a rod 52 to the lever 47.

This lever 47 is in the general form of an 115 angle lever or letter T, the head of which is pivoted at one end and the other end of which is connected to the rod 52, the leg of the T being curved out of a plane and extending between the valve stems 49, 50. The lever 51 is mounted upon the pivot 33 on which the operating lever 30^a for the lock 29 is mounted.

In operation, upon movement of the handle 51 in one direction, the lever 47 is operated to open the valve 49 and hence permit steam to pass through the upper face of the intermediate pressing element 3 when the same is lying on the lower buck 2 and is disconnected from the upper buck 1. 125 130

Upon movement of the handle 51 in the other direction, the valve 46 is opened and permits steam to pass through the passage 20 and through the chamber 22 in the lower 5 side of the intermediate element 3 and pass steam between the lower buck 1 and the intermediate element 3; the lock 29 being now operated to connect the intermediate element 3 to the upper buck 1 so that parts 10 1 and 3 act as a unit.

The pressing elements may be provided with a suitable padding 52 indicated in dotted lines, Fig. 3.

By my invention, the portions of the garment requiring flat pressing and curved pressing can be done on one machine and the machine readily changed at will to perform either operation.

What I claim is:

- 20 1. A garment pressing machine comprising upper and lower pressing elements, the upper pressing element being movable toward and from the lower, an intermediate heated pressing element, movable supports 25 for the upper and intermediate pressing elements, means for connecting and disconnecting the upper and intermediate pressing elements together whereby they move as a unit, means for actuating the support of the upper pressing element and thereby actuating the intermediate pressing element when the same is connected by the former means to the upper pressing element, substantially as and for the purpose described.
- 35 2. A garment pressing machine comprising upper and lower pressing elements, the upper pressing element being movable toward and from the lower, one of said pressing elements being formed with a flat 40 face and the other with a convex face, an intermediate pressing element supportable on the face of the lower pressing element or against the face of the upper pressing element, the intermediate element having a con- 45 cave face on one side conforming to the convex face of one of the former pressing elements and a flat face on the opposite side thereof conforming to the flat face of the other of the former pressing elements, and 50 means for connecting the intermediate element to and disconnecting the same from the upper pressing element, substantially as and for the purpose specified.
3. A garment pressing machine comprising a lower buck having a convex face, an upper buck movable toward and from the lower buck and having a flat face, an intermediate pressing element between the bucks and having a concave lower face conforming 55 to the convex face of the lower buck and a flat upper face conforming to the flat face of the upper buck, and means for connecting said element to and disconnecting the same from the upper buck, substantially as and 60 for the purpose set forth.

4. A pressing machine comprising upper and lower pressing elements having internal heating chambers therein and an intermediate pressing element having an internal heating chamber therein, the intermediate element being supportable on the face of the lower pressing element or against the face of the upper pressing element, and means for connecting and disconnecting the intermediate element and the upper pressing element, substantially as and for the purpose described.

5. A garment pressing machine comprising upper and lower pressing elements, the upper pressing element being movable toward and from the lower and an intermediate pressing element supportable on the face of the lower pressing element or against the face of the upper pressing element, and means for connecting the intermediate element to and disconnecting the same from the upper pressing element, the intermediate element having internal passages for a heating fluid, and perforations in the upper and lower faces thereof, one passage communicating with the perforations in the upper face of the intermediate element, and the other passage with the perforations in the bottom face of said element, and means for controlling the flow of the heated medium through the passages, substantially as and for the purpose specified.

6. A pressing machine comprising upper and lower pressing elements, the upper pressing element being movable toward and from the lower, an intermediate pressing element supportable on the face of the lower pressing element or against the face of the upper pressing element, means for connecting the intermediate element to and disconnecting the same from the upper pressing element, the intermediate pressing element having an internal chamber for a heated fluid, and chambers located on the top and bottom sides of the intermediate element, and having perforated top and bottom walls respectively, a passage communicating with the top chamber, a passage communicating with the bottom chamber, and means for controlling the flow of the fluid selectively through the passages, substantially as and for the purpose set forth.

7. A pressing machine comprising upper and lower bucks, the lower buck being formed with a convex upper face and the upper buck with a flat lower face, an intermediate pressing element supportable on the upper face of the lower buck, or against the lower face of the upper buck, said element having a concave lower face conforming to the convex face of the lower buck and a flat upper face complementary to the flat lower face of the upper buck, the intermediate pressing element having perforated faces on upper and lower sides thereof and internal

passages communicating with the perforations of said faces respectively, means for connecting said element to and disconnecting the same from the upper pressing element, and means for controlling the flow of a heating medium through said passages, substantially as and for the purpose described.

8. A garment pressing machine comprising upper and lower bucks, the upper buck being movable toward and from the lower buck, a pivoted lever carrying the upper buck, an intermediate pressing element located between the bucks, a lever mounted on the axis of the former lever and carrying the intermediate pressing element, and means for connecting and disconnecting said levers together, whereby they move as a unit, substantially as and for the purpose specified.

9. In a garment pressing machine, upper and lower bucks, an intermediate pressing element formed with an internal passage for a heating medium and also with pas-

sages on upper and lower sides thereof, perforated plates closing the sides of the latter chambers communicating respectively with the chambers having the perforated sides, and means for connecting the pressing element to and disconnecting the same from the upper buck, substantially as and for the purpose set forth.

10. A pressing machine comprising upper and lower bucks, an intermediate pressing element between the bucks, formed with a perforated plate on one side thereof and an internal chamber communicating with the perforations of the plate, means for conducting a heating medium to said chamber, and means for connecting the intermediate pressing element and disconnecting the same from the upper buck, substantially as and for the purpose described.

In testimony whereof I have hereunto signed my name, at Syracuse, in the county of Onondaga, and State of New York, this 3rd day of July, 1919.

ALLEN B. PIERCE.
